ATTORNEYS

UNITED STATES PATENT OFFICE.

GEORGE FREDERIC WEST, OF NEW YORK, N. Y.

BROOM.

Application filed April 18, 1922. Serial No. 554,580.

To all whom it may concern:

Be it known that I, GEORGE F. WEST, a citizen of Germany, and a resident of the city of New York, borough of Manhattan, 5 in the county and State of New York, have invented a new and Improved Broom, of which the following is a full, clear, and exact description.

This invention relates to improvements in 10 brooms, an object thereof being to provide a double ended broom connected to a handle in such a manner that the handle may be reversed when one end of the broom head becomes worn and the other end of the head 15 used.

A further object is to provide a broom of this character, which will be by virtue of its construction, extremely durable and serviceable in use, a broom which will not 20 require any specially constructed handle, and one which will be simple and practical in construction, and comparatively inexpensive to manufacture.

With these and other objects in view, the 25 invention consists in certain novel features of construction and combinations and arrangements of parts as will be more fully hereinafter described and pointed out in the claims.

30 In the accompanying drawings:—

Figure 1 is a view in side elevation of my improved broom;

Figure 2 is a similar view with parts of the cloth covering broken away for clear- 35 ness; and

Figure 3 is a transverse sectional view on the line 3—3 of Figure 2.

Referring in detail to the drawings, it 40 will be seen that the head of my improved broom is composed of a number of independent bundles 1 of broom corn or some similar material, these bundles being bound by wire 2, or other suitable flexible devices at their intermediate portions to provide 45 two bushy ends. The bundles 1 are main- tained side by side in operative position by the use of a pair of encircling wire mem- bers 3, 3 wrapped around the intermediate portions of all of the bundles.

50 Transverse tie wires 4 connecting the op- posite sides of the encircling wires 3, 3 lend rigidity and strength to the construction of the broom head, both the tie wires and the wires 3 serving to tightly bind the interme- diate portions of the bundles and to hold 55 the bundles together.

The two pairs of intermediate tie wires 5 provide a space between them for the in- 60 sertion of any suitable handle 6, said handle passing between the two tie wires 5 and be- 65 tween the wires 3 and being attached firmly to the wires 3 by securing devices 7 passed through suitable loops or eyes 8 formed in the intermediate portions of the wires 3 for 70 their reception. It will be evident that the 75 broom handle may be inserted from either end of the broom head and that the bundles provide two bushy sweeping ends, either of which, may be selectively used. Preferably 80 those ends of the bundles which are not 85 used for sweeping are concealed and pro- 90 tected by a cloth covering 9 having an open- 95 ing 10 therein to accommodate the broom handle and snugly accommodating the 100 bristles of the broom head. Obviously when one end of the broom becomes worn, the cloth may be removed, the handle detached, the broom head reversed and again attached to the handle, after which the cloth may be inserted over the other end of the broom 105 head.

I do not wish to limit myself to any par- 110 ticular method of forming the broom heads, but I have found it very convenient to com- press the intermediate portions of the 115 bundles simultaneously in a single mold leaving a space for the insertion of the han- 120 dle. The wires 2 and 3 may be wrapped 125 around the bundles while they are still in 130 the mold.

I have illustrated one of the preferred 135 embodiments of the invention, but numerous slight changes and alterations might be 140 made in the general form and arrangement 145 of the parts described without departing 150 from the invention, and hence I do not wish 155 to limit myself to the precise details set 160 forth, but shall consider myself at liberty 165 to make such slight changes and alterations 170 as fairly fall within the spirit and scope of 175 the appended claims.

I claim:

1. A broom including a plurality of bristles combined to form a broom head ca- 180 pable of being reversed to permit of the use 185 of either end of the broom for sweeping, a binding element extending about said 190 bristles medially of the ends thereof, a plu- 195 rality of bracing elements joining said bind- 200 ing member at opposite points and extend- 205 ing transversely between the bristles of said 210 head, a broom handle capable of being in-

serted into either end of said broom head and between adjacent bracing elements, and means engaging said binding member and extending through said handle for removably securing the latter in operative position with respect to the head.

2. A broom including a plurality of bristles combined to form a head capable of being reversed to permit of the use of either end of the broom for sweeping, a pair of spaced binding members encircling said bristles medially of the ends thereof, a

plurality of tie wires joining oppositely disposed points of each of said binding members and extending transversely between the bristles of said head, and a handle capable of being inserted into either end of said head and between adjacent and corresponding tie wires carried by both of said binding members, and means removably engaging each binding member and extending through said handle to maintain the latter in operative position with respect to the head.

GEORGE FREDERIC WEST.
